UNITED STATES PATENT OFFICE.

THOMAS J. BOTTOMLEY, OF BURLINGTON, WISCONSIN, ASSIGNOR TO
PRATT & LETCHWORTH, OF BUFFALO, NEW YORK.

IMPROVEMENT IN TUG-HOLDERS.

Specification forming part of Letters Patent No. 67,489, dated August 6, 1867; reissue No. 5,657, dated November 18, 1873; application filed August 18, 1873.

To all whom it may concern:

Be it known that I, THOMAS J. BOTTOMLEY, of Burlington, in the county of Racine and State of Wisconsin, have invented a Tug-Holder or Trace-Carrier, of which the following is a specification:

The invention consists of an attachment to harness of horses, whereby the tugs or traces, when unhitched from the whiffle-tree, are securely held up and carried free from the ground, and out of the way of the horse's feet and legs.

In the accompanying drawings, Figure 1 is a side elevation of my attachment. Fig. 2 is a plan; and Figs. 3 and 4 are horizontal sections in lines *x x* and *y y*, Fig. 1.

Like letters of reference designate like parts in each of the figures.

As represented in the drawings, A is the base-ring. *b b* are two trace-carrying arms, supported by four legs, *c c*, connecting with the base A. D is a central post, in the upper end of which is pivoted two spring arms or levers *e e*, the free ends of which connect with the trace-carriers *b*, and form a bridge over the space between the said trace-carriers.

My trace carrier or holder is designed to be attached to the back or crupper strap of harness, at or near the point where the hip-straps

connect with or cross the same. The portions *a a* of the base-ring, between the points where the legs *c* connect therewith, form means for readily attaching or securing my holder to the harness.

The eyes of the tugs or traces are engaged with the carriers *b* by pressing them against the spring-arms *e* so as to swing the latter inward, when the return of the spring-arms to their normal position prevents the accidental detachment of the tugs from the carriers *b*, which support them.

I do not intend to limit myself to the particular form and construction of the parts shown in the accompanying drawings; but

What I claim as my invention is—

1. The combination of two trace-carrying arms with a base, A, provided with loops *a a* substantially as hereinbefore set forth.
2. The combination, with the base and tug-supporting arms of a trace-carrier, of the spring locking-arms *e e*, substantially as and for the purpose hereinbefore set forth.

THOMAS J. BOTTOMLEY.
